UNITED STATES PATENT OFFICE.

HORACE J. CLARK, OF WESTFIELD, NEW YORK.

ROCK-DRILL.

SPECIFICATION forming part of Letters Patent No. 351,310, dated October 19, 1886.

Application filed March 27, 1886. Serial No. 196,771. (No model.)

To all whom it may concern:

Be it known that I, HORACE J. CLARK, a citizen of the United States, residing at Westfield, in the county of Chautauqua, State of New York, have invented certain new and useful Improvements in Rock-Drills, of which the following is a specification, reference being had therein to the accompanying drawings.

This invention has relation to steam rock-drills; and it has for its object, among other things, a simplification of the construction, a reduction in the number of parts, in the weight of the machine as a whole, and in the necessary consumption of steam in operating the same, and the application of power in giving the blow or operating a stroke of the drill in such manner as to reduce to the minimum or entirely overcome any recoil of such blow which will operate to lift the machine or strain it in any of its parts. Heretofore in rock-drills of this character it has been necessary to load the same by attaching weights to the legs of the tripod or machine-support, and it has been necessary to employ steam not only to produce the operating-stroke of the drill, but to employ the same steam at the same pressure to lift the drill for a successive stroke, and in such cases it is apparent that at the completion of each stroke of the drill there is still exerted thereon a greater portion of, if not the entire, pressure exerted by the steam, whereby a powerful recoil, having a tendency to lift the machine, occurs at each stroke of the drill. By my invention I avoid these and other disadvantages in the operation of steam rock-drills and secure other benefits hereinafter specified.

Referring to the drawings, Figure 1 is a substantially central vertical section of a steam-drill embodying my invention, the supporting mechanism being detached. Fig. 2 is a side elevation. Fig. 3 is a side elevation of the supporting and anchoring mechanism, the framework being shown in section. Fig. 4 is a side elevation showing the means for rotating the drill. Fig. 5 is a plan of the foot-piece. Fig. 6 is a detail showing the leg-clamping device, and Fig. 7 is a side elevation of one of the cylinder-head bolts.

Like letters indicate like parts in all the figures of the drawings.

In this instance I embody the novel features of my invention in that class of steam rock-drills in which the drill A', Fig. 3, is secured to a reciprocating cylinder, A, in any suitable manner, or by means of a threaded connection of the drill with the cylinder, as shown. The cylinder is mounted in the frame-work B, which may be cast in a single piece and severed at its lower end diametrically, as on the line B', Fig. 2, in order to provide suitable leg-clamping mechanism, as hereinafter described; or the frame-work may be formed in halves provided with flanges and secured together by bolts, as is customary in the construction of cast-metal frame-work in all classes of machines. The main portion of the frame-work is in this instance made open, and is of such circumferential extent as is necessary to give a sufficient bearing-surface for the cylinder in its reciprocation, and at the upper part is provided with handles B², and with a valve-chest, B³, and ports B⁴ B⁵. At the extreme upper end the frame-work is provided with a stuffing-box, B⁶, for the valve stem.

At the center of the head of the frame-work is secured a fixed tubular piston-rod, C, provided with ports C' near the upper face of the piston C'. Encircling the piston-rod is a sleeve, D, which is secured to the frame-work, or which may be formed as a part thereof, and this sleeve is screw-threaded and has mounted thereon a nut, D'. The cylinder-head A² is apertured to snugly fit the piston-rod, and may be provided with a suitable stuffing-box, if desired. A coiled spring, E, is arranged between the nut D' and the cylinder-head. In this instance, in order to provide for an automatic drill-rotating mechanism, I have mounted on the cylinder-head A² a flanged collar, F', against which the spring E bears, thus providing for the free rotation of the drill-turning disk F, mounted on the head below the flange of the collar F', whereby said disk F may have a slight rising-and-falling movement with relation to the sleeve and collar, and also a free rotary movement by means of devices herein-after described.

The valve G consists of a simple open-ended cylinder arranged in the valve-chest B³, and connected with the valve-stem G' in any suitable manner, in this instance by means of a

spider, G^2 , at the upper end of the valve, into which the valve-stem is screw-threaded and secured by nuts. The port B^4 is the supply-port, and is formed to deliver steam at the top of the valve, while the port B^5 is the exhaust-port, and these are proportioned with the valve, so that each is closed while the other is open.

H is a rod extending from the valve-stem to the tappet-rod I , which in this instance passes through the handle B^2 , and is provided with a long pinion, I' , meshing with a gear, I^2 , mounted on the handle. The upper end of the tappet-rod is provided with a thumb-nut, I^3 . By these devices—that is, either by the pinion I' and gear I^2 , or by the thumb nut I^3 alone—the tappet-rod I may be rotated, and being screw-threaded, as at I^4 , where the tappet-block J' , carrying the tappet J , is mounted thereon, the length of the stroke of the cylinder, and consequently the supply of steam entering the cylinder, may be regulated. The tappet J projects into the path of the cylinder A , so that when the same is elevated the tappet-rod I is also elevated, and through the medium of the bar or rod H elevates the valve-stem and valve to cut off the supply of steam. The lower end of the tappet-rod is provided with an inward bend, I^5 , which projects beneath or into the path of the cylinder, so as to be struck by the same at the completion of a downward reciprocation thereof, and thus communicate motion to the valve G through the medium of the tappet-rod, bar H , and valve-stem G' , whereby the valve is depressed and steam admitted into the cylinder between the fixed piston-head and the upper head of the cylinder.

The means for supporting the drill consist of legs K , which are adapted to fit vertically-bored lugs B^1 , formed as a part of the frame-work and located at its lower end, which is perforated, as at B^8 , for the passage therethrough of the drill. As before stated, the lower end of the frame is divided diametrically on the line B' , so that the perforated lugs are also divided, and in said lower end, and passing through the same, is a bolt, L , which is curved at L' , to conform to the opening B^8 in the frame. A hand or other nut or nuts, L^2 , serve to bind the two parts of the frame together, and thus secure the legs K in the lugs. This binding action is intended to be such that the frame-work may be gradually and intermittently moved or driven down the legs by contact of the lower cylinder-head thereon, or upon any suitable cushion interposed between said head and the frame, as is customary, whereby as the hole drilled in the rock increases in depth an automatic advancement of the drill is secured.

M represents a base or foot piece which I employ, and into which each of the legs K is inserted and fixed, either by a screw-thread, as shown, or by any other suitable means. The foot-piece M has a central aperture, M' , which merges into slots M^2 , and it also has

perforations M^3 for the reception of clamping-hooks N , which are adjustably secured by means of nuts N^1 N^2 , the latter being set or binding nuts, which may be mounted directly on the hooks, or upon bolts extending upwardly from the base-piece and through the slots M^2 thereof, as shown at the right of Fig. 3.

The binding-hooks may be either right angular in form, as shown at the right of said figure, or inclined, so as to take under, as hereinafter described. Telescopic or other guy rods, O , may be employed in connection with the legs, if desired, and in this instance they are pivotally secured to the upper ends thereof, as at O' , and are jointed, as at O^2 , so as to give freedom of motion in any direction, in order to support the machine at different inclinations. To facilitate such dispositions of the machine, the legs K may be pivotally secured to the foot-piece by means of bolts P , passing through the legs and foot-piece, the latter being apertured to permit of oscillation of the legs upon the bolts.

It now remains to describe the drill-turning device, and this consists of the disk F , hereinafter mentioned, mounted loosely upon the upper cylinder-head. This disk has upon its lower surface ratchet-teeth F' , which take into ratchet-teeth Q , arranged upon the cylinder-head. In this instance I utilize the cylinder-head bolts, and form them with an inclined face, Q' , and a vertical face, Q^2 , so that they perform the usual function of securing the cylinder-head to the cylinder and the additional function of ratchet-teeth. The edge of the plate F is provided with lugs F^2 , which embrace the edges of a diagonally disposed or curved cam-bar, R , secured at each end to opposite sides of the frame-work, whereby rotation is given to the disk, as hereinafter described. The ratchet-plate F is mounted loosely, so that at a sudden downward movement of the cylinder it is disconnected from the ratchet-teeth or bolts on the cylinder-head, whereby the drill is not rotated during an operative stroke.

This being the construction, the operation is as follows: Steam entering the port B^4 , the cylinder being down, and through the devices hereinbefore mentioned determining the position of the valve-passage, said steam passes over the upper end of the valve and down into and through the same, and into and through the hollow fixed piston-rod, and from thence out of the ports C' , and therein exerts pressure against the upper surface of the fixed piston and the under surface of the upper piston-head, whereby the cylinder, with the drill attached, is forced upwardly in the frame-work, and compresses the spring E , so as to store therein substantially as much power as there is pressure of steam. Upon rising, the bolt-heads Q' mesh with the ratchet-teeth F' on the disk F , so that the lugs of said disk, riding the cam-bar R , cause the disk, the cylinder, and the drill attached thereto to make a partial rotation, the extent of which is in accordance

with the inclination of the cam-bar, whereby the drill is caused to make its next stroke or cut upon a different line from its preceding stroke. As the cylinder comes in contact with the tappet J the valve is raised and the supply cut off and the exhaust-port opened and the power stored in the spring forces the cylinder and drill downward to their work, when the former, coming in contact with the frame, causes it to slip down the legs just the depth of the cut. To start the drill, the operator, taking hold of the handles, first drills the anchor-holes S, Fig. 3, either straight or with an under-ent, as desired. He then enters the hooks N and binds the foot-piece to the rock, when the regular work of drilling may be carried on, as shown at T, without further manual attendance.

During the course of the work, in case a hard stratum is struck in the rock, or in case of other variations in its texture, it may be necessary or advisable to change the power of the stroke. In order to accomplish this, the operator has simply to either turn the gear I², which constitutes in other respects a handle, or the thumb-nut I³, to raise or lower the tappet J, whereby more or less steam may be allowed to enter the cylinder, as desired, and in accordance with the requirements of the work.

In actual use a drill constructed upon the principles herein illustrated has demonstrated the existence of inherent advantages of great importance.

It will be noticed that steam is only used upon one side of the piston-head, so that the air confined in the cylinder below said head acts as a cushion, against which the stoppage of the upward reciprocation of the cylinder takes place, thereby obviating a tendency to lift the machine by the momentum of the cylinder during that stroke. This tendency is further overcome by the resistance of the spring, as the power stored therein increases during the upward stroke of the cylinder. Again, the blow of a spring has an inherent peculiarity, in that the power stored therein diminishes rapidly to zero as the spring expands, so that when the blow is struck by the spring there is no surplus force remaining to exert a lifting action upon the machine as a whole. By means of the adjusting-nut D', I am enabled to adapt springs of different tensions to use, and to adapt all springs to store a desired amount of power within a desired length of stroke of the cylinder, whereby I may give exceedingly strong blows with exceedingly short strokes of the cylinder, and may otherwise vary the operation of the machine in these respects.

The mode of operation above described renders absolutely unnecessary the attachment of any extraneous weight or weights to the machine, in order to counteract any tendency thereof to lift at any time during its operation, and although I have shown anchorage devices consisting of the foot-piece and hooks, I wish it distinctly understood that they are

designed for the purpose of enabling one operator to attend several machines, as this cannot be done without some device for maintaining the machine in the desired position, which of course must accord with the direction in which the drilling is to take place; otherwise all that is necessary to a satisfactory operation of the machine is that legs K be attached thereto, so as to be automatically shortened at successive strokes of the machine. Another peculiarity is that steam is used to cause but one movement of the operative parts thereof—that is, to lift the cylinder and store the power in the spring, while in other classes of steam-drills steam has been used to perform this function and also the function of giving that stroke of the operative parts, whereby double the quantity of steam is required in such machines as compared with a machine constructed in accordance with my invention.

U, Fig. 2, represents an ordinary angle-valve applied to the machine, the stem of which is provided with the usual hand-wheel, U', whereby the supply of steam may be regulated by the operator, and that conveniently. This valve is attached to the supply-port of the valve-chest.

Having described my invention and its operation, what I claim is—

1. In a steam rock-drill, the combination of a fixed hollow piston with ports at the upper side of the head, a reciprocating cylinder carrying the drill, and a spring arranged to be compressed by an upward movement of the cylinder, substantially as specified.

2. In a steam rock-drill, a cylinder carrying the drill, a fixed piston and a piston-head, and a spring, and steam-conduits arranged to deliver steam at one side of the piston only, substantially as specified.

3. In a steam rock-drill, a cylinder carrying the drill and a fixed piston mounted in a frame-work, an interposed spring, and means for adjusting the pressure of the spring upon the cylinder, substantially as specified.

4. In a steam rock-drill, a cylinder carrying the drill and a fixed piston and head, a frame-work provided with bearings for the cylinder and carrying the fixed piston-rod, and an adjustable tappet projecting into the path of the cylinder, substantially as specified.

5. In a rock-drill, a reciprocating cylinder carrying the drill, a frame-work provided with bearings for the cylinder and carrying a fixed piston-head, and a hollow piston provided with ports above the head only, a spring arranged to bear upon the cylinder, and a tappet-rod provided with tappets projecting into the path of the cylinder and connected with a valve for controlling the supply and exhaust of steam, substantially as specified.

6. In a steam rock-drill, a frame provided with a valve-chest, and with a hollow piston communicating therewith, and having ports above the piston-head, and with supply and exhaust ports, the former arranged at the upper

- and the latter at the lower part of the valve-chest, said frame being provided at its lower end with leg-clamping lugs, substantially as specified.
5. 7. In a steam rock-drill, a tappet-rod having a tappet mounted upon a screw-thread formed on the rod and having a pinion, in combination with the valve, its stem, and the rod connecting said stem with the tappet-rod, 10 and with means for rotating the tappet-rod, substantially as specified.
8. In a steam rock-drill, a reciprocating cylinder carrying the drill and provided with ratchet-teeth upon its upper head, a ratchet- 15 disk mounted upon said head and adapted to have slight longitudinal movement, and a cam bar or rod secured to the frame in which the cylinder is mounted, substantially as specified.
9. The combination of the cylinder A, the 20 frame B, tappet-rod I, carrying the tappets I⁵ J, the bar H, valve G, and the hollow-piston C, having the ports C', and piston C², substantially as specified.
10. The combination of the frame B, the 25 handle B², tappet-rod I, having the opening I', and the gear I², mounted on the handle, substantially as specified.
11. The combination of the cylinder-head A², the bolts Q, the collar E', the disk F, hav- ing the teeth F' and lugs F², and the cam-bar 30 R, substantially as specified.
12. The combination of the frame B, piston C, sleeve D, nut D', and cylinder A, carrying the drill A', substantially as specified.
13. An anchor for steam rock-drills, comprising a foot-piece connected with the legs of a drill, and hooks mounted in the foot-piece and adapted to be drawn outwardly and adjustably secured, substantially as specified. 35
14. The combination of the foot-piece M', 40 having the slots M², with the hooks N, nuts N', and binding-nuts N², substantially as specified.
15. The combination of the frame B, provided with the lugs B⁷, of the bolt L and legs 45 K, substantially as specified.
16. The open-ended tubular valve, in combination with the hollow piston-rod having ports only above the piston-head, and with an exterior tappet-rod having tappets projecting into the path of the cylinder, substantially as specified. 50

In testimony whereof I affix my signature in presence of two witnesses.
